DUAL REMOTE-CONTROL APPARATUS

Michel N. Yardeny, New York, N. Y.

Application May 5, 1944, Serial No. 534,226

4 Claims. (Cl. 172—239)

1

My invention relates to dual control apparatus and particularly to control apparatus for controlling drive means placing a useful load in a desired position.

One object of my invention is to provide a control apparatus comprising a control device for placing the useful load in one of several predetermined positions, a second control device for placing the load in any desired position, and switch means for selectively connecting the drive means for operating the useful load with one or the other of the control devices.

Another object of my invention is to provide a switch mechanism inter-connecting the two control devices whereby one device is rendered inoperative when the switch is closed for the other device.

Another object of my invention is to provide means to render the drive means automatically inoperative when the useful load is placed in the desired position.

Another object of my invention is to provide means to prevent hunting of the motor when the useful load is placed in the desired position. I have found that a very effective arrangement for this purpose comprises means for reducing the rate of movements of the drive means when the desired position is approached, particularly after each reversal of rotation. If a motor is used as drive means, the speed reduction is preferably effected by operating the motor at intervals, for example, by periodic interruptions of the current of the motor by an interrupter or governor causing a deceleration of the motor speed almost to the stopping point between the impulses of energy so that the motor can be readily stopped when the useful load approaches the desired position.

I also provide a reversible switch which short circuits the interrupter or governor during steady rotation of the motor but renders the interrupter operative immediately after each reversal of the motor rotation, such an operation continuing for a limited period of time.

Under certain conditions of operation of the second control device, it may be desirable to operate the load motor through a resistor or other suitable impedance, short circuiting the resistance when the motor must be operated at high speed.

Another object of my invention is to provide indicating means which will indicate the true position of the load, whether it is operated by the first or second control device. Two forms of indicating means may be used, one directly

2

connected to the load shaft and the other electrically controlled by the load shaft.

My invention is more fully described in the accompanying specification and drawings in which—

Fig. 1 is a diagrammatic view of my system in which two control devices may be employed alternatively for operating a useful load, and

Fig. 2 is a fractional detail view of control elements.

My control apparatus as shown in Fig. 1 comprises two units, one, designated generally I, is a control device of a predetermined position type for placing a useful load 5 in any one of a series of predetermined positions, and the other, designated generally II, is a second control device of a continuous or "follow-up" type, for placing the load 5 in any desired position.

The predetermined position control unit includes a number of control selectors or units, each selector comprising a pair of metal segments 6, 7, 8, 9 mounted on insulation discs 10, 11 and separated by gaps 12, 13. The segments are engaged preferably slidably by contact arms 17, 18 with contact point 19, preferably in the form of balls (Fig. 2) which can short circuit or bridge the gaps between the segments. The segments 6, 7 are connected by leads 20, 21 and switches 22, 23, with ends of relay coils 24, 25 the other ends of the coils being connected together by a lead 26 which in turn is connected by leads 27, 28 with a terminal 30 of a source of current. Segments 8, 9 are connected with the relay coils 24, 25 by leads 32, 33 and switches 34, 35. The contact arms 17, 18 are connected by leads 36, 37, 86, point 144, switch 87 and lead 38 with the other terminal 40 of the source of current. The relay coils control arms 41, 42, normally engaging contact points 43, 44, connected with reversing windings 45, 46 of a motor, generally designated 14, the common point of the windings being connected to one terminal of an armature 47, the other terminal being connected by a lead 48. The motor shaft 54 is connected through a transmission 58, 59 with a drive shaft 60 rigidly connected with the contact arms 17, 18 and arranged to operate the useful load 5.

The relay contact arms 41, 42 are connected by leads 62, 63 with contact brushes 64, 65 engaging collector rings 66, 67 of a centrifugal governor 68 mounted on the shaft 54. The ring 66 is connected with inner and outer contact points 70, 71 respectively, the inner points being normally engaged by an arcuate spring 72 sup-

ported in the middle on a post 73, connected with the collector ring 67.

The leads 62, 63 are also connected by leads 76, 77 with a reversible switch comprising resilient contact arms 78, 79. The arms are short circuited by a contact finger 80 extending from a collar or bushing 81 frictionally mounted on a shaft 15. The shaft 15 is provided with a pinion or wheel 59 frictionally or otherwise engaging a wheel 93 on the shaft 60. The wheel 93 may be provided with extensions for indicating its position with reference to a stationary mark 95.

It will be apparent that the finger 80 closes the contact between one pair of arms 78, 79 for either direction of rotation of the shaft 60, being held by stops 82 or 83, both arms being separated for a short time only during the reversal of the motor rotation.

The reversible switch contact points 78, 79 are connected with the brushes 64, 65 of the governor by leads 76, 77, 84, and a switch 75. The switch 75 is preferably mechanically connected with the switches 22, 23, 34, 35, the connections being diagrammatically shown with dotted lines in Fig. 1 and so arranged that the switch 75 may be automatically closed when one pair of the switches 22, 23 or 34, 35 is closed. The switch 75 may be also mechanically connected with a switch 87 which connects the lead 88 with the lead 38 when the control unit I is being operated. Lead 88 is connected with contact points 89, 90 engaged by the relay arms 41, 42 when the latter are attracted by the respective relay coils. For placing the device II in operation, therefore, it is only necessary to move the switch 87 to the right, the other switches being then automatically placed in the correct position, i. e., the switches 22, 23 and 34, 35 opened, and the switch 75 disconnects the reversing switch.

The pairs of switches 22, 23 and 34, 35 are operated by handles 85, 86. The switch 87 is so coupled that it opens the follow-up circuits when any of the pairs of switches 22, 23 or 34, 35 is closed. All the switches 22, 23, 34, 35 and 75 are opened when the switch 87 closes the continuous or follow-up circuit.

The operation of the part I of the control apparatus is as follows:

In order to place the load 5 in a desired predetermined position, the corresponding pair of switches 22, 23 or 34, 35 is closed by operating handle 85 or 86. Switch 75 will be closed and switch 87 turned to the left, disconnecting the second control device. Assuming that the switches 22, 23 are closed and arm 17 engages segment 7, electric current will flow from the terminal 40 by leads 32, switch 87, contact point 144, leads 88, 37, 36, arm 17, segment 7, lead 21, switch 23, coil 25, leads 26, 27, 28 to the other terminal 30 of the source of current. The energized relay coil 25 will attract the relay arm 42 into engagement with the contact point 90. As a result, current will flow from the terminal 40 through the lead 33, closed switch 87, contact point 144, lead 88, point 80, relay contact arm 42, leads 63, 84, switch 75, lead 77, closed contact arms 78, 79 (which short circuit the interrupter or governor 68), leads 76, arm 41, point 43, winding 45, armature 47, leads 48, 28 to the other terminal 30 of the source of current. The motor will rotate, direction of its rotation being so arranged that the contact arm 17 will be moved toward the corresponding gap 12. As soon as the contact arm 17 reaches the gap 12, its point or ball 19 will engage or bridge both segments 6 and

7, causing both relay coils to be energized. As a result, both arms 41, 42 will be raised, disconnecting or deenergizing the motor, thus causing the motor to stop. In practice, however, due to considerable inertia of the moving parts, the contact arm 17 will overrun the gap before the motor can be stopped, causing the motor to be reversed by engaging the opposite segment 6. During such reversal of the rotation, the finger 80 will leave the post 82, disconnecting the previously engaged contact arms 78, 79 until it is stopped by the other post 83. Due to the current interruption at the points 78, 79 during the reversal, interrupter or governor 68 will be operative. The spring 72 will open the motor circuit at the points 70 at a relatively low speed in response to the centrifugal force so that the motor will be operated and rotate at a greatly reduced speed, making it possible to prevent overrunning of the gap by the contact arm 17 when the gap is again reached. The spring 72 may be so adjusted that the motor speed will fluctuate between the interruptions of the current from a low minimum to a relatively high maximum, the average being a small fraction of the normal speed. The motor may be even stopped between the impulses by the combined action of the brake and the interrupter.

The outer control points 71 will carry a heavy current during the current reversal period and before the reversal of rotation, thereby safeguarding the points 78, 79 against heavy current, these points being of a lighter construction. Conventional spark suppressing means may be also provided across the contact points 43, 89 and 44, 90 in the form of condensers and resistors (not shown) which will be effective for the current interruption at the governor, the relay contact points, and at the reversing switch.

An indicating disc 93 calibrated in suitable units such as degrees of a circle may be mounted on the shaft 60, the position of the disc or of the shaft 60 being indicated against a stationary mark or point 95.

The load may be manually operated by turning a shaft 96 with a wheel 97 engaging frictionally or otherwise the disc 93. Switches 22, 23 and 34, 35 must be opened for the manual operation.

The described arrangement, generally designated I is used for placing the load 5 in one of several predetermined or preselected positions as controlled by switches 22, 23, etc., placed at a control point. Under certain conditions, however, it may be desired to place the load in any desired position which is accomplished by means of the second control unit generally designated II. This second unit comprises a pair of metal segments 110, 111 separated by a gap 112 and mounted on an insulation disc 113, rotatively supported on an axis concentric with a shaft 114. The latter carries a contact arm 115 engaging the segments. The disc 113 is engaged by a pinion 118 on a shaft 119 operatively connected with an armature 120 of a control motor having a permanent field magnet 121 and generally designated 116. The segments 110, 111 are connected with collector rings 122, 123 engaged by the contact brushes 124, 125 connected by leads 126, 127 with the ends of relay coils 129, 130. The other ends of the coils are connected by a common lead 131 with the lead 28. The coils 129, 130 are also connected by leads 132, 133 with the corresponding relay coils 24, 25 which control the load motor 14.

The armature 120 of the control motor 116 is connected by leads 135, 136 with contact arms

139, 140, normally engaging contact points 137, 138 connected by a lead 158 with the lead 28, the arms being operated by the relay coils 129, 130. The other contact points 141, 142 are connected by leads 143 and 160 with the contact arm 115 and with a contact point 162 of the switch 87.

It should be noted that while the speed of the motor 14 may be satisfactory for the operation of the control system I, it may be too high for the operation of the system II for the accurate placement of the load in any desired position. Means are provided therefore for materially reducing the motor speed when the system II is in operation and for facilitating stopping of the motor at any moment. Under certain operating conditions this may be accomplished by causing the interrupter or governor 68 to operate continuously when the system II is used, for which purpose the switch 75 may be mechanically connected with the switch 87 so that it opens the circuit of the reversible switch contacts 78, 79, between the leads 84 and 71. The motor then will rotate at short intervals, at a fluctuating speed, the speed dropping to a relatively low value between current impulses. The motor under such conditions will stop instantly when the gap is bridged by the contact arm, without any tendency to oscillate or hunt. An additional switch 99, short circuiting the leads 150, 147 may be then kept closed. By opening the switch 99, a resistor or similar impedance 161 will be included in the motor circuit, still further decreasing the motor speed.

If a greater torque is desired for operating the load by the motor 14, the switch 75 may be disconnected from the switch 87 and left closed when the system II is operating, leaving also open switch 99. The motor 14 will then operate through the resistor 161 until its reversal after the contact arm 115 passes the gap by inertia and when the interrupter 68 will be rendered inoperative.

A supplementary governor or interrupter 153 is mounted on the shaft 119 of the motor 116, connected by a switch 100 with the leads 147, 150. The interrupter is provided with contact points 158 connected with a collector ring 155, an arcuate spring 159 being connected with a collector ring 156. The rings are engaged by brushes 179, 171 connected with the leads 147, 150 through the switch 100.

An additional switch 192 with contact point 193 is provided between the leads 150, 88 for disconnecting the resistor 161 when the unit I is operated. This switch is also mechanically connected with switches 87 and 144.

In view of the fact that the position of the load motor 14 may not correspond to the position of the control motor 116 or of the disc 113, it is necessary to have an indicator 172 at the point of control operated by a potentiometer or similar device 173 at the load. The potentiometer is connected with the source of current by leads 175, 176, the source of current being also connected by a lead 178 with the meter or indicator 172. The motor shaft 60 is connected with a contact arm 180 of the potentiometer, the arm being connected by a lead 181 with the meter 172. A zero adjusting resistor 182 may be provided in the lead 178. The indicator may be calibrated in any suitable units for indicating the exact position of the load 5.

The operation of the control system II is as follows:

Switches 87 and 75 are turned to the right for

engaging the points 162, 148 respectively, disconnecting at the same time all the switches of the system I, i. e., 22, 23 and 34, 35.

Switch 99 may be closed, short circuiting the resistor 161, if high speed is desired, or it may be opened for operating the motor 14 through the resistance. Switch 100 may be left opened if it is not desired to use the interrupter 153.

The arm 115 is then manually moved to the right or to the left, depending on the direction in which it is desired to move the load 5. Assuming that the contact arm 115 is moved to the right and now engages the segment 111, current will flow from the terminal 40 through the lead 38, switch 87, point 162, lead 160, contact arm 115, segment 111, brush 125, lead 127, relay coil 138 and leads 131, 28 to the terminal 30. The relay arm 140 will be attracted, engaging the point 142.

The current will also flow from the switch 87 through the point 162, leads 160, 143, contact point 142 raised arm 140 (the relay coil 130 being now energized), lead 136, control motor armature 120, lead 135 arm 139, point 137 and leads 158 and 28 to the terminal 30 of the source of current. The coil 25 will be energized simultaneously with the coil 130 through the leads 133, 21, 28 attracting the arm 42 and causing the armature 47 of the load motor 14 to rotate. The load motor 14 will be energized as described above with the exception that the current will now flow through the interrupter 68. The load motor therefore will receive the current impulses through the interrupter and will rotate at a relatively slow rate. The armature 120 of the motor 116 will rotate in a direction for causing the disc 113 with the segments to follow the displaced contact arm 115. When the gap 112 catches up with the contact arm 115 and the gap is bridged both pairs of the relay coils 129, 130 and 24, 25 will be energized. Both contact arms 138, 140 will be attracted, short circuiting the armature 120 by the lead 143 and thereby positively stopping the armature by dynamic braking due to the action of the magnetic field of the permanent magnet 121. The armature 47 will be stopped simultaneously with the armature 120 of the control motor when the gap 112 is bridged. Position of the load motor and of the load can be then observed on the dial of the indicator 172.

To prevent the contact arm 115 from being moved manually too far over the segments 110, 111 and to be placed on the opposite segment, causing reversal of the motor, the segments are provided with raised portions or stops 185, 186 (Fig. 2).

The segments 110, 111 as well as the segments 5, 7 and 8, 9 of the unit I are provided with raised ends 187, 188 at the gap as shown in Fig. 2 for yieldingly retaining the ball 19 of a contact arm in the gap when the gap is bridged and the motor shall be stopped. Such an arrangement materially helps to suppress the tendency of the motor to oscillate or hunt when a gap is reached by a contact arm.

The raised portions 187, 188 also serve to retain the contact ball 19 as shown in dotted lines in Fig. 2, the arm 115 being then dragged along by the rotating disc 113 until the shaft 114 is manually stopped at the approach of the indicator pointer to a desired position.

By opening both switches 99 and 100, the interrupter 153 will be rendered operative. Switch 75 must be also opened for this operation, switch 87 being moved together with the switch 87. The

contact spring 159 is normally disengaged from the contact points 158 connecting the motor 14 through the resistor 161. After the motor 116, however, reaches its normal speed, the spring 159 will be deflected by the centrifugal force, engaging the contact point 158 and short circuiting the resistance. The motor 14 will then operate at a normal speed until the gap 112 is bridged by the ball 19 (Fig. 2) of the contact arm 115, causing both motors to stop. If the arm 115 is again moved, the motors will start, resistance 161 being included in the motor circuit. The interrupter 153 will therefore function as a brake, introducing resistance at the time when the motor must be stopped.

The following main combinations are therefore possible with my system for operating the motor 14 through the unit II:

(1) The motor 14 is operated continuously through the governor 68, the reversible switch 78, 79 being disconnected by the switch 74, switch 99 closed.

(2) The same operation, switch 99 opened, switch 100 also opened. The motor 14 is operated at a still further reduced speed through the resistor 161.

(3) The same operation, switch 99 opened, switch 100 closed. The motor 14 will receive intermittent current impulses after each start or reversal, making it easy to stop the motor at the exact moment when the desired position is reached by the load.

It will be understood that various features and principles of each of the embodiments of the invention above described or referred to may be utilized or substituted in other embodiments.

While the invention has been described in detail with respect to certain particular preferred examples, it will be understood by those skilled in the art after understanding the invention, various changes and further modifications may be made without departing from the spirit and scope of the invention, and it is intended therefore in the appended claims to cover all such changes and modifications.

What is claimed as new and desired to be secured by Letters Patent is:

1. In a system for positioning from a control point a load at a remote point to a selected one of a plurality of predetermined positions or to any desired position, in combination, a reversible motor for moving the load, a plurality of selectors at the remote point each comprising a pair of members, one of the members having a pair of electrical conducting segments separated by a gap and the other member having a contact element engageable therewith, one of the members of the said plurality of selectors being pre-set to cause displacement between the said gaps and said contact elements of the respective selectors according to the said plurality of predetermined positions, switch means at the control point selectively operated to place the load motor under control of a desired one of the said plurality of selectors at the remote point to cause directional rotation of the motor to move the load to a predetermined position corresponding to the operated one of the said plurality of selectors at the remote point, and the other member being operatively connected to the said load motor for rotation in a direction to restore alignment between the gap and contact element of the operated selector to stop motor rotation, the said other member overrunning the gap to cause reversal in motor rotation, speed reducing means,

responsive to said reversal to render the said speed reducing means operative for a limited time, a pair of relatively movable members at the control point for moving the load to any desired position, one of the last named members having a pair of electrical conducting segments separated by a gap, the said conducting segments being electrically connected to the load motor at the remote point, and the other member having a contact engageable with the said conducting segments, one of the members being selectively adjusted to engage the said contact element with one or the other of the conducting segments for directional rotation of the load motor, a pilot motor at the control point operatively connected to the other of the said pair of members to restore alignment between said contact element and gap to stop rotation of the said load and pilot motor with the load at the desired position, switch means at the control point selectively operated to place the load motor under control of the said pair of relatively movable members at the control point or under control of the said plurality of selectors at the remote point said second switch means rendering the said speed reducing means continuously effective when the load motor is under control of the said pair of relatively movable members at the control point.

2. The combination according to claim 1 wherein the said speed reducing means is a rotary speed governor.

3. In a system for positioning from a control point a load at a remote point to a selected one of a plurality of predetermined positions or to any desired position, in combination, a reversible motor for moving the load, a plurality of selectors at the remote point each comprising a pair of members, one of the members having a pair of electrical conducting segments separated by a gap and the other member having a contact element engageable therewith, one of the members of the said plurality of selectors being pre-set to cause displacement between the said gaps and said contact elements of the respective selectors according to the said plurality of predetermined positions, switch means at the control point selectively operated to place the load motor under control of a desired one of the said plurality of selectors at the remote point to cause directional rotation of the motor to move the load to a predetermined position corresponding to the operated one of the said plurality of selectors at the remote point, and the other member being operatively connected to the said load motor for rotation in a direction to restore alignment between the gap and contact element of the operated selector to stop motor rotation, the said other member overrunning the gap to cause reversal in motor rotation, speed reducing means, a by-pass circuit rendering the said speed reducing means normally inoperative, means responsive to said reversal to open the said by-pass circuit to render the said speed reducing means operative for a limited period, a pair of relatively movable members at the control point for moving the load to any desired position, one of the last named members having a pair of electrical conducting segments separated by a gap, the said conducting segments being electrically connected to the load motor at the remote point, and the other member having a contact engageable with the said conducting segments, one of the members being selectively adjusted to engage the said contact element with one or the other of the conducting segments for directional rotation of the load motor.

tion of the load motor, a pilot motor at the control point operatively connected to the other of the said pair of members to restore alignment between said contact element and gap to stop rotation of the said load and pilot motor with the load at the desired position, switch means at the control point selectively operated to place the load motor under control of the said pair of relatively movable members at the control point or under control of the said plurality of selectors at the remote point said second switch means opening the said by-pass circuit to render the said speed reducing means continuously effective when the load motor is under control of the said pair of relatively movable members at the control point.

4. In a system for positioning from a control point a load at a remote point to a predetermined position or to any desired position, in combination, a reversible motor for moving the load, a selector at the remote point having a neutral position and comprising a pair of relatively movable members, one of the members being pre-set to control directional rotation of the said load motor to move the load to the said predetermined position, and the other member being driven by the load motor in a direction to restore the said selector to its said neutral position to stop motor rotation, the said other member overrunning the neutral position to cause reversal in motor rotation, speed reducing means, means responsive to said reversal to render the said speed reducing means operative, a control device at the control point having a neutral position and comprising a pair of relatively movable members, one of the

15

20

25

30

35

members being selectively adjusted to control directional rotation of the said load motor to move the load to a desired position, means at the control point for moving the other member in a direction to restore the said control device to its said neutral position to stop motor rotation, and switch means at the control point selectively operated to place the load motor under control of the said device at the control point or under control of the said selector at the remote point, said switch means rendering the said speed reducing means continuously operative when the load motor is under control of the said device at the control point.
